UNITED STATES PATENT OFFICE.

ENDRE A. LANSRUD, OF DES MOINES, IOWA.

AUTOMATIC SAND VALVE.

Application filed April 11, 1925. Serial No. 22,277.

The object of my invention is to provide a sand structure including a valve or series of valves, the whole being comparatively simple and inexpensive and being adapted for the accurate and easy grading and sizing of sand.

A further object is to provide in connection with a chute or the like a series of valves automatically operated by the flow of sand and water for separating the sand into grades and sizes without the using of rolling or other screens or the like.

With these and other objects in view, my invention consists in the construction, arrangement and combination of the various parts of my automatic sand structure, whereby the objects contemplated are attained, as hereinafter more fully set forth, pointed out in my claims, and illustrated in the accompanying drawings, in which:

Figure 1 shows a side elevation of a device embodying my invention.

Figure 2 is a top or plan view of a portion of the chute equipped with my invention proved valve structure, parts being broken away.

Figure 3 is a longitudinal, detailed, sectional view taken on the line 3-3 of Figure 2.

Figure 4 is a detailed, sectional view taken on the line 4-4 of Figure 3; and

Figure 5 is a horizontal, sectional view taken on the line 5-5 of Figure 4.

In the practice of my invention, I preferably use a long inclined chute by which sand and water are carried. The chute is shown for instance in Figure 1, as indicated by the reference character 10.

For reasons which will be apparent in the course of the explanation of my invention, it is desirable that the chute should be somewhat adjustable as to degree of inclination from the horizontal.

For purposes of illustration, I have shown in the drawings herewith a series of spaced concrete posts 11, 12 and 13 for supporting the chute. These are preferably wide enough so that channel irons may be fastened to them in opposite spaced pairs projecting substantially above the posts and adapted in the case of each pair to extend on opposite sides of the chute 10. The channel irons are indicated by the number 14.

In the particular illustration of my invention shown herein, I have shown the posts 11, 12 and 13 of increasingly greater

heights. The channel irons 14 are preferably in each instance provided with a series of holes 15. Rods or the like 16 may be extended between the channel irons of each pair just below the chute or trough 10.

The chute is held against sliding downwardly for instance by links 17 pivoted to the lower channel irons 14 and to the trough.

For controlling the tilting movement of the trough, I have secured to the lower end thereof a pair of cables 18. Each cable 18 is secured to one side of the trough and then extended over a pulley 19 on one of the channel irons 14 of the lower post 11, thence around the pulley 20 on the chute, thence over a pulley 21 on the channel iron of the next post 12, and thence around a pulley 22 on the chute or on one of the valve hoppers 29, thence over a pulley 23 on the channel of the post 13 and thence around a drum 24 at the upper end of the chute. The drum 24 may be actuated by means of a worm wheel 25 and worm 26 and crank 27.

If it is desired to raise the chute bodily, this may be done by winding the cables 18 upon the drums 24.

By inserting a stop rod through the proper holes 15 above the chute at the upper or lower ends thereof, then when the cables are tightened, the other end of the chute will be raised for giving the chute any desired angle of inclination.

The chute may be manipulated with a crane or in any suitable way.

At suitable intervals spaced lengthwise of the chute, the bottom of the chute is provided with an opening 28 from which there extends downwardly a somewhat tapered hopper casing or discharge chute 29.

For regulating the flow of sand into each hopper 29, I provide slide valve plates or the like 30 and 31, slidably mounted on the floor of the chute 10 above and below the hopper 29 under consideration and adapted to slide over the opening 28 for leaving a discharge opening of any desired width.

The plates 31 are provided with fastening bolts 33 which project through longitudinally elongated slots 34 in the bottom of the chute 10, as shown in Figure 3, and are provided with washers 35 and thumb nuts or the like 36.

Mounted on the lower end of each hopper 29 is a substantially cylindrical casing or valve chamber 37 open at its upper

end and having a closed lower end 38 provided with a central downward tubular extension 39, the lower end of which forms a valve seat.

5 At the upper end of the casing member 37 is a table 40 capable of limited vertical movement. The table 40 has a central open downwardly extending tubular portion or member 41 extending almost to the lower part of the 10 casing member 37 and open at its lower end.

The table 40 stands normally about level with the joint between the casing member 37 and the hopper 29.

The table 40 is of smaller diameter than the 15 lower end of the hopper 29 and has a flexible member 42 of canvas or the like secured to its edge by means of a clamping plate or the like 43, which is held in place by means of screw bolts 44 or any suitable means.

20 The outer edge of the canvas member 42 is clamped between the upper edge of the casing member 37 and the lower edge of the hopper 29, as shown in Figure 3. The flexible connecting member 42 between the table 25 40 and the walls of the hopper is so arranged that it has slack when the table is in position level with the outer edge of the flexible member. This permits the table to move to position above or below such outer edge during the operation of the device.

Secured to the four corners of the table 40 are upwardly extending converging hangers or arms 45 in the form of rods connected at their upper end by means of a bolt 46.

35 Supported on the bolt 47 is a rod 47 forming a valve stem on the lower end of which is a valve 48 adjustable on the stem 47 by means of a thumb nut 49 and intended to contact with the valve seat 50 formed at the lower end of the extension 39 of the casing member 37.

On the bolt 46 is a clevis 51 to which is connected a rod 52 which extends upwardly through a fixed sleeve 53 supported by rods 54 on the walls of the hopper 29. The sleeve 53 extends upwardly above the level of the material flowing through the chute 10 and the rod 52 projects upwardly from the sleeve as shown in Figure 3, and is pivoted at its 50 upper end to a balance arm 55. The balance arm 55 is pivotally supported on a bracket 56 on a cross bar 57 at the top of the chute 10. On the balance arm 55 is an adjustable weight 58.

55 It should perhaps be mentioned that the sliding plate members 30 and 31 are provided with notches 59 to receive the sleeve 53, so that the opening above any particular hopper 29 may be closed if desired.

60 In the practical use of my improved structure, the plates 30 and 31 are adjusted to give openings 32 of the desired sizes. The weight 58 is adjusted and when the water and sand flow downwardly through the chute 10, the 65 coarsest sand will drop into the first or up-

per hopper, the next size into the next lower hopper and so on. The very finest sand can be taken from the lowermost hopper 29, if desired.

I find that it is necessary to keep the valve 70 hopper 29 substantially filled with water. By adjustment of the weight 58, the automatic valve can be set to keep the sand on the table 40 at any desired weight or depth.

It is desirable, of course, that the sand 75 should pass out in as nearly a steady stream as possible.

In actual practice, I find that by properly adjusting the parts, the sand on the platform 80 40 will lower the platform and thus open the valve 48 for allowing sand to flow through an extension 41 and the extension 39 past the valve, and then the weight 58 will raise the platform again.

In the actual use of this device, there is 85 almost a continuous up and down movement of the platform 40, so that the flow of sand from each hopper is almost continuous. The hopper 29 is thus kept filled with water and yet the sand is constantly discharging therefrom.

90 Adjustment may be had by varying the size of the opening 32 and further adjustment may be had by regulating the position of the weight 58, and adjustability may be had for varying conditions in different locations by regulating the angle of inclination of the chute 10.

With a little experience, the operator can take from any flowing quantity of sand 100 through the different hoppers 29 just the grade of sand desired.

I find a large number of advantages in the use of the structure herein described.

The grading of the sand is very accurately accomplished. It is done with a minimum of wear on the machinery. Sand can be separated and graded with this device much cheaper than with the rotating screens which are commonly used. This is especially true with all fine grades of sand.

I also find it possible with this device to separate the fine sand, so that it is in a distinct and separate body. This has heretofore been very difficult. The fine sand, if entirely unmixed with coarser sand is saleable, but fine sand mixed with coarser sand does not find a very ready market.

It will be noted that by providing the automatic valve structure at the lower part 120 of the hopper 29 with the extension 41 into the casing member 37, there will be no flow of sand until the sand on the table or platform 40 reaches a certain weight.

125 It may be mentioned that I find in practice that the sand 60 does not collect in any great quantity in the casing member 37, but such casing member is always filled with water before sand reaches it.

Changes may be made in the construction 130

and arrangement of the various parts of my device without departing from the real spirit and purpose of my invention. In fact it has been my purpose to illustrate a structure in which my invention may be embodied in and according to which the desired functions may be performed, but it is my purpose to cover by my claims, any such modified forms of structure or use of mechanical equivalents, as may be reasonably included within their scope.

I claim as my invention:

1. In a device of the class described, the combination of an inclined chute, a tapered hopper therebelow, opening into the chute, means for adjusting the size of the opening between the chute and the hopper, an extension on said hopper, a platform in said hopper having a flexible adjustable connection 20 with the hopper wall and having a central tubular downward extension terminating near the bottom of the hopper extension, a tubular downward extension on said hopper extension forming at its lower end a valve 25 seat, a valve for coacting with said seat, means for supporting said valve to move with said platform, and a counter-balanced arm for supporting the platform.

2. In a structure of the class described, an inclined chute, a hopper extending downwardly from the bottom thereof and communicating therewith, means for varying the size of the opening from the chute into the hopper, a movable platform at the lower end 35 of said hopper, a valve operatively connected with said platform for controlling flow of material from the bottom of the hopper, and means for regulating the position of said platform according to the weight imposed 40 thereon.

3. In a device of the class described, a supporting means, a hopper supported thereon with a central, downwardly projecting tubular extension at its bottom, a flexible platform received in the hopper having a central, downwardly, extending tubular extension for limiting flow of sand into the hopper below said platform and thus preventing interference with the movement of the platform, means for adjusting the position of said platform, and a valve for said first tubular extension movable with the platform.

4. In a device of the class described, a hopper having at its bottom a downwardly projecting tubular outlet passage, a platform in said hopper having a central, substantially rigid portion provided with a central, down-

wardly extending tubular passage, and having a peripheral flexible portion, and means for vertically adjusting said platform, and a valve movable with said means for connecting flow from said outlet passage.

5. In a device of the class described, a hopper having at its bottom a downwardly extending tubular outlet passage, a flexible platform in said hopper having a central, downwardly projecting tubular passage above said first passage, a plurality of spaced arms secured to said platform and converging upwardly, means connected with the upper ends of said arms for vertically adjusting the platform, and a valve movable with said platform for controlling flow from said outlet passage.

6. In a device of the class described, an inclined chute, a hopper therebelow communicating therewith, means for regulating the size of the opening between the chute and the hopper, said hopper having an opening at its bottom, a valve for controlling said opening, and means for controlling said valve according to the weight of the material in the hopper, said hopper and valve structure being entirely supported on the chute, and means for adjusting the angle of inclination of the chute.

7. In a device of the class described, an inclined chute, a hopper therebelow communicating therewith, means for regulating the size of the opening between the chute and the hopper, said hopper having an opening at its bottom, a valve for controlling said opening, and means for controlling said valve according to the weight of material in the hopper, said hopper and valve structure being entirely supported on the chute, said chute being tiltable for varying its angle of inclination.

8. In a device of the class described, a hopper having at its bottom a downwardly extending tubular outlet passage, a flexible platform in said hopper having a central, downwardly projecting tubular passage above said first passage, a plurality of spaced arms secured to said platform and converging upwardly, means connected with the upper ends of said arms for vertically adjusting the platform, a valve movable with said platform for controlling flow from said outlet passage, and a counter-balancing device operatively connected with said means having an adjustable counter-balancing element.

Des Moines, Iowa, February 19, 1925.
